UNITED STATES PATENT OFFICE.

CLARENCE H. MORROW, OF CLEVELAND, OHIO, ASSIGNOR TO THE HOTSTREAM HEATER COMPANY, OF CLEVELAND, OHIO, A CORPORATION OF OHIO.

BURNER.

Application filed November 25, 1927. Serial No. 235,603.

This invention relates to burners and particularly to that type which utilizes a mixture of air and gas.

The general object of the present invention is the provision of a burner of the type described which is of simple and inexpensive construction capable of being made in one piece by a simple casting operation; and which burner is provided with fuel discharge orifices and air openings so arranged and of such number as to insure proper combustion and the production of a uniform flame over the entire burner area.

Other details of the invention will be brought out in connection with the following description, drawings and claim.

Referring to the drawings, Fig. 1 is a top plan view of the burner with parts broken away; Fig. 2 is a side elevation with parts broken away; and Fig. 3 is a vertical cross section.

The burner illustrated in the drawings is a one piece metal casting and comprises a chambered member generally circular in plan view and provided centrally with a depending tubular portion 2 adapted to be removably mounted upon the upper end of a fuel supply pipe 1. Said member is also provided with an outer annular rim portion 3 and three hollow cross arms 4 at right angles to each other in grid arrangement. One of said arms extends diametrically and the other two arms extend normal thereto in parallel relation and on opposite sides of the diameter, all as clearly shown in Fig. 1.

The upper walls of the hollow cross arms and the annular rim are each provided with two rows of projections 6 having fuel discharge orifices 7 and said cross arms and rim are separated by a series of six air openings 5. Two of said openings, the ones between the parallel cross arms, are

generally rectangular in shape while the remaining four openings are generally triangular in shape. At the center, the upper wall of the burner member is imperforate and substantially flat, as clearly shown in Fig. 3.

By this arrangement it will be seen that an ample supply of air for combustion will pass through the burner and be delivered to the burner projections which are close to the edges of the rim and the cross arms, thus producing a uniform flame over the entire burner area.

What I claim is:

A gas burner, comprising a hollow chambered member generally round in plan view and provided centrally with a depending tubular portion adapted for connection to a fuel supply pipe and having a passage communicating with said chamber and above said passage being provided with a central imperforate upper wall, said hollow member having an outer annular rim portion and a plurality of hollow cross arms at right angles to each other in grid arrangement, one extending diametrically and two at right angles thereto, being parallel and on opposite sides of the diameter, the upper walls of the hollow cross arms and the annular rim being each provided with two rows of jet orifices, and the several cross arms and the rim being separated by a series of six openings, two generally rectangular and four generally triangular in shape, thereby uniformly distributing gas throughout the inner chamber and abundantly supplying air through said six openings and distributing the same uniformly to all of the jet orifices and thus producing a uniform flame over the entire burner area.

In testimony whereof I hereby affix my signature.

CLARENCE H. MORROW.
